UNITED STATES PATENT OFFICE.

CHARLES LAMBERTY, OF BROOKLYN, NEW YORK.

BURGLAR-ALARM.

SPECIFICATION forming part of Letters Patent No. 357,837, dated February 15, 1887.

Application filed August 12, 1886. Serial No. 210,708. (No model.)

To all whom it may concern:

Be it known that I, CHARLES LAMBERTY, a citizen of the United States, residing in Brooklyn, in the county of Kings and State of New York, have invented certain new and useful Improvements in Burglar-Alarms, of which the following is a specification.

My invention relates to that class of burglar-alarms which are arranged to be suspended to the spindle of a door, so that when the knob is turned by any one desiring to enter the room the alarm is set in operation.

The invention consists, principally, in suspending a weight or pendulum within the case 15 of the apparatus, which tends to remain at all times in a perpendicular position. The alarm-train is operated by a spring. When wound and secured to the door-spindle, it is kept from running down by a pin upon the scape-wheel, which engages a pin upon the rod which carries the weight. As soon as the knob is turned the weight and its rod change 20 their positions, the scape-wheel is released, and the alarm is sounded. When once started, 25 a device prevents it from being stopped by any movement of the knob; but it continues until the spring is unwound or until some one on the same side of the door as the alarm arrests it.

30 In the accompanying drawings, which illustrate my invention, Figure 1 is a front view of the alarm suspended from the spindle of the door. Fig. 2 is a back view showing the arrangement of the train and weight, and Fig. 35 is a side view of the same.

Referring to the drawings, A represents the door-knob; a, the spindle; B, the gong; C, the case of the alarm; D, the principal wheel of the alarm-train, and s the scape-wheel. At 40 the top of the case of the alarm the arm m is rigidly fixed, and m' is pivoted thereto at n. These arms are made to clasp tightly the spindle of the door-knob by means of the thumbscrew t and the screw-rod r, which latter 45 passes through m', and is pivoted to m at m'. When the alarm is suspended, it hangs in an approximately perpendicular position, as shown in the drawings. The weight W is freely suspended upon the rod w at the point 50 e. The arm F is fixed to the rod w at right angles thereto. Upon the scape-wheel s are

one or more pins, p. When both the case C of the alarm and the rod w are in a perpendicular position, the pin p' upon the end of the arm F is in the path of the pins p, and will 55 engage one of them; but if the case and the rod w change their relative positions by the movement of the weight W toward either side the pin p' is carried either above or below the pin p, and the scape-wheel is released. The 60 spring S is wound by applying a key to the spindle k in the usual manner, k' being the usual retaining-pawl. V is the vibrating-lever-escapement.

It is evident that when the door-knob is 65 turned the case of the alarm, being rigidly attached to the spindle a, is turned with it; but the weight W, being freely suspended from the point e, will preserve its perpendicular position, and will turn the arm F, thus releasing 70 the scape-wheels. At the point v, where the vibrating lever V is pivoted, the rod v' is rigidly attached to V, and the hammer H of the gong is caused to vibrate as V is vibrated by the rotation of the scape-wheel s. The hammer H is within the gong B, and strikes the latter with each movement, causing, when the scape-wheel is in motion, a rapid succession 75 of strokes.

An arm, R, is loosely pivoted upon the screw 80 r' and extends across the case, the end r'' passing out through an opening at o. The arm R has near its center the slot y, and a pin, p'', upon the rod w slides within the slot y. When the rod w is in a perpendicular position, the 85 pin p'' is in the position shown—that is, at the bottom of the slot—but if the weight W moves toward either side the pin p'' slides toward one of the points y' or y''. Any slight movement of the weight W is sufficient to carry the pin 90 p'' into one or the other of these positions, and when it reaches either it is at once held in that position, as the shape of the slot at the ends will not permit it to return, so that when p'' has once reached the point y' or y'' the scape-wheel 95 is free to revolve until the spring is run down. If the knob is turned back to its former position, so that the case of the alarm is again in a perpendicular position, the weight W is simply held out of its perpendicular position so 100 long as the pin p'' is held at y' or y''. It will be seen that when the pin p'' moves either way

within the slot y the arm R will be pushed downward, and when p^2 is at y' or y^2 the end of the arm R will be about at the bottom of the opening o in the side of the case. By raising the 5 end r^2 of the arm R the pin p^2 may be released from y' or y^2 , and brought into its middle position at the bottom of the slot, as shown in the drawings. This brings the pin p' upon the arm F into the path of the pin p upon the 10 scape-wheel and the alarm is stopped.

When the alarm is fixed ready for operation, the arm R is in the position in the middle of the opening o , as shown. When it is desired to lock the alarm so that turning the knob will 15 not cause it to operate, the end r^2 of the arm R is lifted to the top of the opening o , and is held there by the catch k' . In that position the weight is rigidly held in position and the door can be opened without affecting the alarm.

20 I claim as my invention—

1. The combination, in a burglar-alarm, of arms attached to the case of the alarm for clasping the spindle of a door-knob, a weight or pendulum suspended from said case, a train of 25 wheels and a gong, a spring for actuating the same, and a device connected with said pendulum for normally locking said train and for releasing the same when the weight is moved.

2. In a burglar-alarm, the combination of 30 arms for clasping the spindle of a door-knob, which are rigidly attached to the case of the alarm, a train of wheels and a gong, a spring for actuating the same, a suspended weight or pendulum, a device connected with said pendulum for causing the alarm-train to be set in 35

operation when said pendulum moves from a perpendicular position, and a device for preventing the return of said weight to a perpendicular position after it has left the same.

3. The combination, in a burglar-alarm, of 40 arms for clasping the spindle of a door-knob, a train of wheels and a gong, a spring for actuating the same, a suspended weight or pendulum, a device connected with said pendulum for causing the alarm to be set in operation 45 when said pendulum moves from a perpendicular position, and the arm R, with device for engaging the pendulum-rod, whereby the return of said weight to a perpendicular position is prevented after it has left the same, and 50 whereby the action of said alarm may be manually arrested.

4. The combination, substantially as hereinbefore set forth, of the alarm-case C, the arms m and m' , and the screw-rod r , and thumb-screw t , for attaching the alarm to the spindle of door-knob, the suspended weight W, the train of wheels, the gong, the arm F, carrying the pin p' , for engaging a stop upon the scape-wheel, and the arm R, having the V-shaped slot for engaging the pin p^2 upon the pendulum-rod, which said arm R extends outside the case of the alarm. 55

In testimony whereof I have hereunto subscribed my name this 10th day of August, A. 60 D. 1886.

CHARLES LAMBERTY.
